UNITED STATES PATENT OFFICE.

OLIVER VANORMAN, OF RACINE, WISCONSIN.

PLATFORM-WAGON GEAR.

SPECIFICATION forming part of Letters Patent No. 247,443, dated September 20, 1881.

Application filed June 11, 1881. (Model.)

To all whom it may concern:

Be it known that I, OLIVER VANORMAN, of Racine, in the county of Racine, and in the State of Wisconsin, have invented certain new and useful Improvements in Platform-Wagons; and I do hereby declare that the following is a full, clear, and exact description thereof.

My invention relates to platform-wagons of that class in which there is a hinged connection between the body and front gear, and will be fully described hereinafter.

In the drawings, Figure 1 is a plan view of the front gear of my platform-wagon. Fig. 2 is a vertical cross-section of the same, taken 15 on the line $y-y$; and Fig. 3 is a longitudinal vertical section taken on the line $x-x$ of Fig. 1. Fig. 4 is a bottom view of the oscillating plate, and Fig. 5 is a detail sectional view.

Like letters refer to the same parts in all the 20 figures of the drawings.

A is what is termed a "platform" in the class of wagons to which my invention applies, and the platform A carries the usual circle, A', supported on the curved pieces A'' A'' and cross-piece B'. The center piece, B, of the platform assists in supporting the cross-piece B', which is re-enforced at b, and is provided with a hub, b', in which is a hole for the king-bolt to pass through. The top of the re-enforce is flattened 25 about the hub b' to afford a bearing for the center of an oscillating plate, C, which is reamed out at c to admit the hub b', and is slotted at d to allow the king-bolt D to pass through it. The under side of the oscillating plate C is beveled to a central apex, which forms its bearing 30 when the front wheels of the wagon are on a level with each other; but when one of the front wheels is elevated by an obstruction the platform will tip up, and, instead of raising 35 that side of the body, will merely change its point of contact with the plate C from the

ridge or apex on the bottom of the plate to one of its sides, the slot d in plate C allowing the king-bolt D sufficient lateral play to prevent any strain on the body, even when the 45 axle is tilted to an angle of forty-five degrees.

The oscillator plate C is provided at each end with a pair of lugs, E E, in which are journaled rollers E', generally flanged, as shown, and these rollers travel on the circle A', their 50 flanges tending to hold them in place and to relieve the king-bolt of lateral strain.

An ordinary T-bolt, secured to the upper side of the oscillator-plate, serves as a medium for connecting it with the wagon-body. 55

What I claim as my invention, and desire to secure by Letters Patent, is—

1. The combination, with the front gear of a platform-wagon having re-enforced center piece, B' b, and hub b', of a circle, A', and an 60 oscillator-plate, C, carrying rollers at each end, and formed with a beveled bearing on its under side and a cone-shaped socket adapted to fit over the hub b', as set forth.

2. The oscillator-plate C, beveled to a knife-edge on its under side at the center, and provided with a cone-shaped socket and a beveled slot to receive the hub and king-bolt of a platform gear respectively, as set forth. 65

3. The combination, in a platform-wagon, of 70 the circle A', oscillator-plate C, having rollers E' at each end, and beveled under side bearing, conical socket, and beveled slot at its center, with the cross-piece B', having re-enforce b and hub b', and the king-bolt D, as set forth. 75

In testimony that I claim the foregoing I have hereunto set my hand this 27th day of May, 1881.

OLIVER VANORMAN.
